SEALING HEAD MECHANISM FOR CLOSING
AND SEALING BAGS AND CONTAINERS

August E. Almgren, Hillside, and John P. Jakob, Roselle, N. J., assignors to American Can Company, New York, N. Y., a corporation of New Jersey

Application December 17, 1947, Serial No. 792,122

11 Claims. (Cl. 93—6)

1

This invention relates to a sealing head mechanism for folding and sealing flexible containers such as filled paper bags and has particular reference to the folding of a marginal edge portion of a bag in such a manner as to provide corner pleats. Reference is here made to our copending United States applications Serial Number 792,123, filed December 17, 1947, on Bag Sealing Machine; Serial Number 792,124, filed December 17, 1947, on Bag Sealing Machine; and Serial Number 792,125, filed December 17, 1947, for Method of Sealing Bags.

An object of the invention is the provision of a mechanism for folding and sealing the open end of a bag or container filled with articles such as cans by folding or turning-in corner sections of the marginal edge portion of the bag independently of adjacent side sections thereby forming lapping folds at the corners which are sealed easily during the folding operation.

Another object of the invention is the provision in a mechanism of the character described, of a plurality of elements for turning or folding-in sections of the marginal edge portion at the corners of the bag in advance of the remaining intermediate or side sections to form overlapping folds or pleats on the turned-in corners of the bag and to seal the turned-in sections onto an inserted board or bag end member.

Numerous other objects and advantages of the invention will be apparent as it is better understood from the following description, which, taken in connection with the accompanying drawings, discloses a preferred embodiment thereof.

Referring to the drawings:

Figure 1 is a side elevational view of a bag closing and sealing mechanism embodying the present invention;

Fig. 2 is a perspective view illustrating the upper open end of a bag filled with cans preparatory to being sealed;

Fig. 3 is a view similar to Fig. 2 showing the bag closed and sealed;

Figs. 4, 5 and 6 are perspective views illustrating a corner of the bag and showing how the marginal corner and marginal side sections are folded into sealing position;

Fig. 7 is an enlarged sectional view showing a pleated corner fold taken substantially along the line 7—7 in Fig. 3;

Fig. 8 is an enlarged top plan view of a sealing head used in the mechanism shown in Fig. 1;

Fig. 9 is an elevational view of the sealing head

2

shown in position for sealing the open end of a filled bag, with parts shown in section;

Fig. 10 is a schematic view showing the details of a piping assembly joining air valves for operating the folding elements in the sealing head; and

Fig. 11 is an enlarged sectional view of one of the valves shown in Fig. 10.

As an exemplary embodiment of the invention 10 the drawings show a sealing head mechanism for closing and sealing a bag or flexible container A (Figs. 1, 2 and 3) of rectangular configuration and preferably made of fibre, which is filled with cans B. The cans are packed in layers with a 15 division or separator sheet between each layer. The top layer of cans is covered with a flat sheet or closure member D having a band of adhesive or glue E on its top surface (Fig. 2) adjacent but in spaced relation to its outer periphery. An 20 upper marginal edge portion C of the bag extends above the end member D and is folded inwardly and downwardly against the adhesive coated end member for sealing the bag.

In folding the marginal edge portion C of the 25 flexible bag down against the closure member D, corner sections F of the marginal edge portion C, are first folded inwardly and downwardly against the closure member D (as shown in Fig. 4). While the folded corners are held in place,

30 intermediate or side sections G are folded inwardly and downwardly against the closure member as shown in Fig. 5. This progressive folding of the marginal edge portion C forms corner pleats J, K which overlap the corner sections F as shown in Figs. 6 and 7 and thus provide 35 a smooth, well formed and secure corner structure. Thereafter these folded edge portions C of the bag are clamped tightly against the end member D for fully creasing the pleats J, K and for effecting proper contact of the folded portions with the adhesive on the end member. This completes the sealing of the bag.

A preferred form of sealing head mechanism 40 for folding and sealing the marginal edge portion C of a filled bag A includes a rectangular shaped hollow sealing head frame 22 (Figs. 1 and 8) which is secured to a support arm 23 of a vertically movable slide 24, carried on a frame 25 which constitutes the main frame of the machine.

The sealing head frame 22 preferably is movable relative to and away from a filled bag A to be sealed, the bag being located beneath the head frame on a platform 26 mounted on the upper end of a stem 27 carried in a bearing 28 formed 45 on the machine frame 25. The head frame 22

55

may be raised and lowered on the slide frame 25 in any suitable manner. If desired, the head frame 22 may be held stationary and the bag moved up into the frame. For this purpose the platform stem 27 may be raised and lowered in any suitable manner.

As the sealing head frame 22 moves down from the position shown in Fig. 1 onto a filled bag A as shown in Fig. 9, for a sealing operation, the upper marginal edge portion C of the bag is surrounded and guided to maintain it in an upright position and thereby prevent its being crushed. For this purpose an outwardly tapered or flared, rectangular shaped apron or guide 29 is carried on the head frame 22 and hangs down below the frame and telescopes over the end of the bag as the frame moves into sealing position. It is when the head frame 22 is in this sealing position that the marginal edge portion C of the bag is folded inwardly and downwardly against the end member D as hereinbefore explained.

Folding of the bag corners F into place is effected by a plurality of hingeable triangular shaped corner folding elements 32 which are located one at each corner of the head frame 22. These corner folding elements are mounted on pivot pins 33 (Figs. 4, 5 and 6) carried in spaced lugs 34 formed on the head frame 22. The folding face of each element preferably carries a cushion 30 of rubber or other resilient material. The folding elements 32 are actuated by bracket arms 35 which extend outwardly from each of the elements and which are pivotally connected by links 36 to the lower ends of rods 37 having pistons 38 which operate in corner actuating valves 39 (Figs. 10 and 11). There is one of these valves 39 at each corner of the head frame 22.

The upper and lower ends of all the valves 39 are in communication with upper and lower air pipes 40, 41 (see Figs. 10 and 11) having connecting pipes 42, 43 which are communicable with any suitable source of compressed air. A control valve may be connected with the pipes 42, 43 to control the entrance of air into the pipes 40, 41, if desired.

When compressed air is admitted into the upper pipe 40, it forces the pistons 38 down in their valves 39 and thus through the links 36 rock the corner folding elements 32 into a vertical position. This is the normal position of the folding elements. The lower pipe 41 acts as a vent pipe during this movement of the pistons 38. When compressed air is introduced into the lower pipe 41, the upper pipe 42 serves as a vent pipe and thus the pistons 38 are forced upwardly in their valves 39 and this movement of the pistons rocks the corner folding elements 32 downwardly to perform a corner folding operation.

Folding of the side sections G of the marginal edge portion C of the bag is effected by hingeable side folding elements 47 (Figs. 4, 5, 6, 8 and 9). There are four of these side folding elements located along the sides of the head frame 22 intermediate its corners. Each element is formed with a pair of spaced lugs 48 which are mounted on pivot pins 52 carried in brackets 53, secured to the sealing head frame 22. The folding face of each element preferably carries a cushion 54 of rubber or other resilient material.

These side folding elements 47 are actuated by 70 rocker arms 55 which extend out from the elements intermediate their spaced lugs 48 and which are connected by links 57 to the lower ends of piston rods 58 (Fig. 10) having pistons which operate in valves 62 which are similar to the

valves 39. There is one of these valves 62 for each side folding element 47.

The upper and lower ends of all the valves 62 are in communication with upper and lower air pipes 63, 64 (Fig. 10) having connecting pipes 65, 66 which are communicable with any suitable source of compressed air. A control valve may be connected with the pipes 65, 66 to control the entrance of air into the pipes 63, 64, if desired.

10 When compressed air is admitted into the upper pipe 63, it forces down the pistons of the valves 62 and thus through the links 57 rocks the side folding elements 47 into a vertical position. This is the normal position of the side folding elements. 15 The lower pipe 64 acts as a vent pipe during this movement of the pistons. When compressed air is introduced into the lower pipe 64, the upper pipe serves as a vent pipe and thus the pistons are forced upwardly in their valves 62. This movement of the pistons rocks the side folding elements 47 downwardly to perform a side folding operation.

In operation, while the sealing head frame 22 moves downward onto a filled bag A as an incident to sealing the bag, the corner folding elements 32 and the side folding elements 47 are disposed in vertical or retracted position. When the head frame is in sealing position, with the marginal edge portion C of the bag extending up into the frame, the corner portions F are first folded inwardly against the inserted closure member D by an inward and downward arcuate movement of the corner folding elements 32 acting in unison as shown in Fig. 4.

Immediately following the folding-in action of the corner folding elements 32 the side folding elements 47 are swung inwardly and downwardly to fold the side sections G of the marginal edge portion C down against the closure member D as shown in Fig. 5 and this action forms the overlapping pleats J, K previously referred to. In timed relation to the movement of the side folding elements 47 the corner folding elements 32 release their hold on the folded-in corner portions F and are lifted or swung upwardly into a position as best illustrated in Fig. 6 while the side folding elements 47 remain in position and continue to hold down the folded-in side portions G.

The corner folding elements 32 thereafter are swung inwardly a second time. This repeated action presses or creases the overlapping pleats J, K to complete the folded corner pleats as best illustrated in Fig. 7. The corner folding elements 32 and the side folding elements 47 remain in their inwardly swung positions temporarily to hold the folded sections F and G against the closure member D until these parts are fully bonded together.

60 If desired, this holding action may be effected independently of the folding elements through a sealing pad 68 which is movable into position within the rectangular space defined by the inner edges of the corner folding elements 32 and side folding elements 47 (Fig. 8). The sealing pad presses the inner marginal edges of the side, corner and overlapped portions G, and F against the top inserted wall member D to bond these container parts together.

The sealing pad 68 is carried in the sealing head frame 22 on a pair of spaced and parallel vertical rods 72 secured in bosses 73 formed on the pad. Rods 72 are vertically slideable in bearings 74 formed on a bracket 75 secured to the sealing head frame 22 and above the pad. The

sealing pad 68 is normally held in a raised position by springs 76 which surround the rods 72 and which are interposed between each bearing 74, and locknuts 70 secured to the upper end of the rods.

The pad 68 may be lowered manually by a hand crank 77 for bringing the pad into sealing position against the top of the bag. The hand crank 77 is carried on the outer end of a horizontal shaft 78 carried in a pair of spaced bearings 79 in the bracket 75. This shaft carries a pair of cams 82 which operate against cam rollers 83 mounted on pivot pins 84 carried in bosses 85 formed on the upper face of the pad 68. The lower face of the sealing pad is provided with a cushioned facing 86 formed of rubber or other resilient material.

When the sealing pad 68 is moved down onto the bag, it is held there for a predetermined period of time, depending upon the type and setting time of the adhesive being used, thus insuring a proper bonding of the container parts together.

Following the sealing of the bag as explained above, the corner folding elements 32 and the side forming elements 47 are rocked upwardly simultaneously, preparatory to lifting the sealing pad 68 from the sealed bag. After removal of the sealing pad 68, the sealing head frame 22 is lifted from the sealed bag. This completes the cycle of operations of the mechanism.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a mechanism for folding in the ends of tubular members for containers, the combination of a frame for surrounding the open end of a tubular member, corner folding elements carried in said frame for turning-in corner sections of a marginal edge portion of the open end of said member, and side folding elements carried in said frame for folding-in the remaining side sections of said marginal edge portion against said turned in corner sections in overlapping relation thereto.

2. In a mechanism for folding in the ends of tubular members for containers, the combination of a frame for surrounding the open end of a tubular member, corner folding elements pivotally carried in said frame for turning-in corner sections of a marginal edge portion of the open end of the tubular member, side folding elements pivotally carried in said frame for folding in side sections of said marginal edge portion to form corner pleats therein, and means for operating said corner folding elements and said side folding elements in timed relation.

3. In a mechanism for folding and sealing an open end of a bag or other container filled with articles, the combination of a sealing head frame for surrounding the open end of a filled bag to be sealed, corner folding elements pivotally carried in said frame for turning-in corner sections of a marginal edge portion of the open end of the bag and for pressing said sections against an adhesive coated surface and a closure member inserted into said bag, side folding elements pivotally carried in said frame for folding-in side sections of said marginal edge portion against

an adhesive coated surface and said inserted closure member said adhesive lying between said sections and said closure member for sealing the bag, and fluid actuated means for independently operating said corner folding elements and said side folding elements.

4. In a mechanism for folding in the ends of tubular members for containers, the combination of a frame for surrounding the open end of a tubular member, an apron in said frame for guiding a marginal edge portion of the open end of the tubular member into said frame, corner folding elements carried in said frame for turning-in corner sections of said marginal edge portion, and side folding elements carried in said frame for folding-in side sections of said marginal edge portion to form corner pleats therein.
5. In a mechanism for folding and sealing an open end of a bag or other container filled with articles, the combination of a support for a filled bag to be sealed, a sealing head frame movable into position for surrounding the open end of said bag, corner folding elements pivotally carried in said frame for turning-in corner sections of a marginal edge portion of the open end of the bag against an adhesive coated surface and a closure member inserted into the bag, and side folding elements pivotally carried in said frame for folding in side sections of said marginal edge portion against an adhesive coated surface and said closure member to form corner pleats and to seal the bag.
6. In a mechanism for folding and sealing an open end of a bag or other container filled with articles, the combination of a sealing head member for surrounding the open end of a filled bag for sealing, a support member for supporting a filled bag to be sealed, one of said members being movable relative to the other for effecting the sealing, corner folding elements pivotally carried in said sealing head member for turning-in corner sections of a marginal edge portion of the open end of the bag against an adhesive coated surface and a closure member in the bag, and side folding elements pivotally carried in said sealing head member for folding in side sections of said marginal edge portion against an adhesive coated surface and said closure member to form corner pleats and to seal the bag.
7. In a mechanism for folding and sealing an open end of a bag or other container filled with articles, the combination of a sealing head frame movable into position for surrounding the open end of said bag, corner folding elements pivotally carried in said frame for turning-in corner sections of a marginal edge portion of the open end of the bag against an adhesive coated surface and a closure member in said bag, means for operating said corner folding elements, side folding elements pivotally carried in said unit for folding in side sections of said marginal edge portion against an adhesive coated surface and said closure member in said bag, and means for operating said side folding elements independently of said corner folding elements to effect the sealing of the bag.
8. In a mechanism for folding and sealing an open end of a bag or other container filled with articles, the combination of a sealing head frame for surrounding the open end of a filled bag to be sealed, corner folding elements pivotally carried in said frame for turning-in corner sections of a marginal edge portion of the open end of the bag against a closure member having adhesive applied to an area thereof, side folding elements

pivotedly carried in said frame for folding in side sections of said marginal edge portion against said closure member, a sealing pad cooperating with said corner folding elements and said side folding elements for sealing the bag, and means for independently operating said corner folding elements, said side folding elements and said sealing pad.

9. In a mechanism for folding and sealing an open end of a bag or other container filled with articles, the combination of a sealing head frame movable into position for surrounding the open end of a filled bag, corner folding elements pivotally carried in said frame for turning-in corner sections of a marginal edge portion of the open end of the bag against an adhesive coated surface and a closure member in the bag for producing corner pleats and securing the corner sections to the closure member, fluid pressure means for operating said corner folding elements, side folding elements pivotally carried in said frame for folding in side sections of said marginal edge portion against an adhesive coated surface and for securing said side sections to said closure member, fluid pressure means for operating said side folding elements, said fluid pressure means also operating to retract said corner and side folding elements for a repetition of their operation.

10. In a mechanism for folding and sealing an open end of a bag or other container filled with articles, the combination of a sealing head frame movable into position for surrounding the open end of a filled bag, corner folding elements pivotally carried in said frame for turning-in corner

3 sections of a marginal edge portion of the open end of the bag against an adhesive coated surface and a closure member in the bag to produce corner pleats and to secure said corner sections to said closure member, fluid operated pistons for actuating said corner folding elements, side folding elements pivotally carried in said frame for folding in side sections of said marginal edge portion against an adhesive coated surface and said closure member to secure said side sections to said closure member, and fluid operated pistons for actuating said side folding elements.

11. In a mechanism for folding in the ends of tubular members for containers, the combination comprising a frame surrounding the open end of a tubular member, triangular corner folding and pressing elements and side folding elements movably mounted in said frame, means for moving said triangular corner folding elements against corner sections of a marginal edge portion of said open end of the tubular member for turning in said corner sections, means for moving said side folding elements against said side sections of said marginal edge portion for turning in said side sections and forming pleats overlapping said corner sections, said first mentioned means being operable subsequently for retracting said triangular corner folding and pressing elements and for moving them inwardly a second time to press and crease said pleats overlapping said corner sections.

AUGUST E. ALMGREN.
